UNITED STATES PATENT OFFICE

ADOLF DOEBLER, OF KARLSRUHE, GERMANY

HIGH-PRESSURE WATER-TUBE BOILER WITH DIVIDED HEADER

Application filed September 3, 1926, Serial No. 133,414, and in Germany September 7, 1925.

In boilers with divided header of known type the front and rear header divisions are different and, owing to this difference the circulating tubes which connect the header divisions with the boiler drum are different at the front end and at the rear end. In some boiler types more than one circulating tube has been arranged in one header division.

Between the rear header divisions and the boiler drum only one circulating tube could be arranged in one header division; the free cross section of these circulating tubes was consequently smaller than the free cross section of the chamber whereby the return flow of the water to the header divisions was rendered more difficult. The mixture ascending in the front header chambers is further conducted through the front circulation tubes in a direction of flow towards the boiler drum and the steam can separate only in the boiler drum. As the specific gravity of the mixture is lower than that of the water in the boiler drum the water from the boiler drum presses against the inflowing mixture and impedes more or less the circulation. All these inconveniences are obviated, according to the invention, by a special construction of the header-chambers and by a special arrangement of the circulation tubes.

Several embodiments of the invention are shown, by way of example, on the accompanying drawings, in which

Fig. 1 is a side elevation, partly in section, of the preferred form of construction of a high pressure water-tube boiler with divided header, according to the invention.

Fig. 2 shows in side elevation a modified form of construction of the top end of a front header division.

Fig. 3 is a view similar to Fig. 2 showing the front water-tubes arranged at an angle of 45°.

Fig. 4 is a front elevation of Fig. 2. In the water-tube boiler with divided header, according to the invention, the extensions of the header divisions 2, connected to the front and rear ends of the water tubes 1, are bent at the top end at an equal angle in outward direction and the front and rear

chambers are identical as regards shape and size. The special shape of the header divisions makes it possible to arrange at the front and at the rear any number of circulation tubes 3 and 4. The circulation tubes are not soldered at any point to the header divisions but welded in as into the boiler drum. The number of circulation tubes is selected so that the free cross section of the front circulation tubes and of the rear circulation tubes is equal to or greater than the cross section of the header divisions, whereby the water circulation is accelerated. All circulation tubes are quite as easily accessible as the water tubes and it is easy to clean the same. The front circulation tubes are identical to the rear circulation tubes as regards number, size and length.

In the water-tube boiler with divided header, according to the invention, the front circulation tubes, as shown in Fig. 1, are arranged so that they are all situated underneath the water level. The upper ends of the front header divisions are all extended to beyond the water level so that a steam space is produced in each header division. In these upper ends of the header divisions the steam separates from the ascending mixture. The header divisions are then connected at the top ends with the boiler drum 8 by tubes 5 through which the separated steam flows into the boiler drum. From this it results that the whole cross section of the circulation tubes can be utilized for the water circulation.

Each front header division can be connected simply to the boiler drum. The steam might however first be conducted, as shown in Fig. 2, into a steam-collector chamber 6, which is arranged transversely to the header division, and from this collector chamber by one or more tubes 7 to the boiler drum.

The water tubes may be arranged at any angle. Fig. 1 shows that they are arranged at an angle of 30°. The boiler is low in proportion to its length; this boiler construction is consequently well adapted for low boiler-houses. If the water-tubes are arranged, as shown in Fig. 3, at an angle of 45° the rear circulation tubes stand vertical.

By this arrangement the boiler becomes higher but shorter so that it is adapted for high boiler houses with small floor space.

The entire construction of the boiler is extremely simple. Owing to the similarity of the header divisions and to the similar construction of the front and rear circulation tubes the obtention of spare elements is facilitated. As the steam is separated in the front header divisions the front circulation tubes serve exclusively for the circulation of the water and as the downcomers are of at least the same free cross section as the header divisions, the return flow of the water is carried through with certainty down to the lowest water tube. When the boiler is forced, the lower tubes will not become empty, and burning through of the lower water tubes is avoided. As all the circulation tubes and also all the water tubes are easily accessible from the outer side the examination is extremely simple. The boiler does not contain any sensitive points, it is adapted for the highest pressures and the maximum security of service is ensured.

I claim:—

1. A high-pressure compartment water-tube boiler, comprising in combination a transverse boiler drum, front header divisions, an upper extension of each front header division bent upward and extending beyond the water level so that a steam space is formed in the upper end of each extension, a transverse steam collecting element arranged on the upper ends of and connected to said extensions of said front header divisions, upper steam overflow pipes connecting said steam collecting space with the steam space of the boiler drum, and a group of connecting pipes between each front header division and the boiler drum situated underneath the water level of said boiler drum so that said upper steam over-flow pipes serve merely for the circulation of steam, the lower group of connecting pipes serving for the circulation of water.

2. A high pressure compartment water tube boiler comprising in combination with a transverse boiler drum, front header divisions and rear header divisions, upwardly directed and outwardly bent extensions one on each header division, a group of water circulation tubes connecting said extensions of said front header divisions with the water space of said drum, and a group of water circulation tubes connecting said extensions of said rear header divisions with the water space of said boiler drum and being of at least the same free cross section as the adjacent header extensions and corresponding as regards number, size and shape accurately with said water circulation tubes of said front header extensions, and water circulation tubes connecting said front and rear header divisions.

3. A high pressure compartment water tube boiler, comprising in combination with a transverse boiler drum, front header divisions, rear header divisions and boiler tubes connected between said front and rear header division, upwardly directed and outwardly bent extensions one on each header division, a group of water circulation tubes connecting said extensions of said front header divisions with the water space of said boiler drum, and a group of water circulation tubes connecting said extensions of said rear header divisions with the water space of said boiler drum, and being of at least the same free cross section as the adjacent header extensions and corresponding as regards number, size and shape accurately with said water circulation tubes of said front header extensions, said front header divisions and said rear header divisions being of accurately similar size and shape so that in combination with the front and rear water circulation tubes a symmetric structure of boiler is obtained, the symmetry axis of which forms the perpendicular through the center of the boiler drum on the boiler tubes.

In testimony whereof I affix my signature.
ADOLF DOEBLER.
